UNITED STATES PATENT OFFICE.

ADAM ROSS, OF BUFFALO, NEW YORK.

PAPER-WINDING MACHINE.

1,257,404.

Specification of Letters Patent. Patented Feb. 26, 1918.

Application filed February 24, 1917. Serial No. 150,840.

To all whom it may concern:

Be it known that I, ADAM Ross, a citizen of the United States, residing at Buffalo, in the county of Erie and State of New York, have invented new and useful Improvements in Paper-Winding Machines, of which the following is a specification.

This invention relates to a machine for winding strip paper into rolls for use on the headrests of barber chairs so as to render the same sanitary although such rolls may also be used for other purposes. Paper for this purpose is usually supplied by the mills in large rolls and this has to be rewound 15 into a plurality of smaller rolls for more convenient use.

It is the object of this invention to provide a simple, efficient and inexpensive machine whereby paper may be thus rewound easily 20 and conveniently from large rolls into small rolls and thus effect a considerable economy in the cost of making the same.

In the accompanying drawings:

Figure 1 is a side elevation of a paper winding machine embodying my invention. Fig. 2 is a top plan view of the same. Fig. 3 is a fragmentary horizontal section taken on the correspondingly numbered line in Fig. 1. Fig. 4 is a longitudinal section of 30 the machine. Figs. 5 and 6 are vertical transverse sections taken on the correspondingly numbered lines in Fig. 1. Fig. 7 is a perspective view of one of the standards for supporting the arbor of the supply roll of paper. Figs. 8 and 9 are similar views of 35 the two sections of the winding shaft upon which the small rolls are formed.

Similar characters of reference indicate corresponding parts throughout the several 40 views.

The main frame of this machine may be variously constructed but as shown in the drawings the same preferably comprises a hollow rectangular base 1 which is provided 45 on its underside with feet 2 whereby the same may rest on the table or other support, a pair of front standards or uprights 3, 3 projecting upwardly from the front part of the base and a pair of rear standards or up- 50 rights 4, 4, which project upwardly from the rear part of the base. Each of these standards is preferably mounted on the base so as to be capable of transverse adjustment thereon to suit the width of paper which is 55 being rewound. The preferred means whereby this adjustment of each of the standards

relatively to the base of the frame is effected comprises an inwardly projecting flange 5 arranged at the lower end of each standard and provided with two transverse slots 6 and two clamping bolts 7 passing through 60 these slots and into the adjacent part of the base for the purpose of securing this flange to the upper side of the base, as best shown in Figs. 2 and 4-6. By this means the standards of the front pair may be spread apart or moved nearer to each other and the same may also be done with reference to the rear pair of standards by first loosening the clamping bolts and then tightening the same 70 after these standards have been shifted to the desired position to fit the width of the strip of paper which is to be rewound from a large roll into a plurality of small rolls. By this means the machine can be readily 75 adapted to variations in the width of the paper inasmuch as the same does not always come of uniform width from the mills and thereby insures even rewinding of the paper.

The supply roll 8 usually comes from the 80 mill with conical sleeves or bushings 9 engaging frictionally with opposite hollow ends of the roll, as shown in Fig. 6. Preparatory to beginning the rewinding of this roll into small rolls 10 the supply roll is 85 mounted on the rear standards so that the same is freely revoluble thereon for unwinding the strip of paper therefrom. The means for this purpose which are shown in the drawings comprise an arbor 11 which is 90 inserted in the sleeves of the supply roll and has reduced ends 12 which engage with upwardly opening bearing slots 13 arranged in the upper ends of the rear standards. This arbor is coupled with one of the sleeves 95 by a coupling piece 11^a secured to this sleeve and the arbor by screws or the like and the arbor is preferably turned by hand in a direction for unwinding the strip of paper from the supply roll and thus permitting a 100 sufficient amount of slack to be maintained between the supply roll and the rewound roll which will permit the strip of paper to be properly and evenly rewound without requiring any particular care. This turning 105 of the arbor is preferably effected by means of a handle 14 applied to the left hand end of the arbor, as shown in Figs. 2 and 6.

The paper preferably passes from the underside of the supply roll forwardly and 110 around a rewinding shaft which is pivotally mounted horizontally and transversely in

bearings 15 formed in the upper ends of the front standards. This shaft is preferably constructed in two sections 16, 17 the division between which is preferably lengthwise and diametrically through this shaft so as to form two substantially semi-cylindrical sections one of which is preferably provided with a longitudinal rib 18 on its inner side and the other with a longitudinal groove 19 on its inner side, so that the free front end of the strip of paper may be clamped between these sections of this shaft and be compelled to turn therewith. These shaft sections are held in this position with the paper strip gripped between the same by sliding one section lengthwise over the other within the bearings of the front standards, so that these bearings not only serve as journals for this shaft but also operate to hold the two sections of the rewinding shaft in their operative position. One of these shaft sections is provided at one of its ends, preferably the right hand end, with a crank or handle 20 for turning the same and the other section is provided at its opposite end with a lug or fingerpiece 21 so that the same may slide lengthwise on the companion shaft section for engaging the same with the front end of the strip of paper preparatory to beginning the winding of a small roll and also to permit of disengaging the shaft sections from the bore of the small rewound roll after the winding of the same has been completed.

In order to permit of winding the small rolls of the desired diameter a gage device is provided which is so constructed that the same may be set for winding small rolls of different diameters as desired. This gage device preferably comprises a gage plate 22 arranged horizontally between the front standards and below the rewind shaft. When the strip of paper has been wound on the rewind shaft until its diameter is sufficiently great to cause the periphery of this small roll to bear against the gage plate the further turning of this roll is retarded and serves as an indication to the operator that this roll has reached the proper diameter.

For the purpose of permitting the gage plate to be adjusted to suit rewound rolls of different diameters this plate is mounted on the front uprights so as to be capable of vertical adjustment thereon toward and from the rewind shaft. Means suitable for accomplishing this purpose comprise two externally screw threaded clamping shanks 23 projecting outwardly from opposite ends of the gage plate through upright slots 24 in the front standards and two clamping nuts 25 arranged on the outer ends of the clamping shanks and bearing against the outer sides of the front standards, as shown in Figs. 1, 3 and 5. By loosening the clamping nuts 25 this gage plate may be raised and

lowered as desired and then secured in its adjusted position by tightening these nuts.

In order to prevent the front standards from springing inwardly at their upper ends under the pressure of the clamping nuts 25 means are provided which preferably comprise spacing or distance screws 26 arranged in screw threaded openings in opposite ends of the gage plate and bearing at their outer ends against the inner side of the front standards, as shown in Figs. 2 and 3. Whenever therefore the front standards are adjusted transversely on the base to suit a particular width of paper the spacing or distance screws are adjusted on the gage plate so that they engage with the inner sides of the front standards and thereby prevent the upper ends of the same from being drawn inwardly by the pressure of the screw nuts 25 which otherwise would interfere with the free rotation of the rewound roll.

After the strip of paper has been wound on the rewinding shaft and the desired diameter of rewound roll has been obtained on the latter the strip of paper is severed between the supply roll and the rewound roll preferably immediately in rear of the latter so as to permit of completing the rewound roller and starting another roll of like character. Various cutting or severing devices may be employed for this purpose but that shown in the drawings is preferred and is constructed as follows:

27 represents a normally fixed lower cutter bar or blade which is arranged horizontally and transversely adjacent to the rear side of the gage plate and fixedly secured at one end to the left hand front standard by means of a screw 28 while its right hand end is adjustably secured to the right hand standard by means of a screw 29 passing through a longitudinal slot 30 in the corresponding end of the lower cutter blade. 31 represents a movable upper cutter blade which is pivoted on the fixed screw 28 and adapted to be swung upwardly and downwardly across the lower blade by means of a handle 32 applied to the free end thereof. During the rewinding operation the upper cutter blade is swung upwardly and laterally out of the path of the strip of paper so that the same is free to pass from the supply roll to the rewind shaft. After the rewound roll of the proper diameter has been produced on the rewinding shaft the upper cutter blade is swung downwardly past the lower cutter blade, whereby the strip of paper between the same is severed immediately in rear of the rewound roll. By reason of the screw and slot connection between the lower cutter blade and the right front standard, the front standards can be adjusted transversely of the machine without interfering with the cutter mechanism.

As a whole this paper rewinding apparatus is very simple in construction, the same can be produced at comparatively low cost, it can be readily adjusted to suit different widths of paper and also to obtain rewound rolls of different diameters, the same contains no delicate parts which are liable to get out of order, and it permits of producing small paper rolls more economically than has been possible heretofore.

I claim as my invention:

1. A paper winding machine comprising a winding shaft, standards provided with bearings in which said shaft is journaled and also provided with upright slots, a gage plate arranged between said standards and provided with threaded shanks arranged in said slots, and clamping screw nuts applied to said shanks and engaging with the outer sides of said standards.

2. A paper winding machine comprising a winding shaft, standards provided with bearings in which said shaft is journaled and also provided with upright slots, a gage plate arranged between said standards and

provided with threaded shanks arranged in said slots, clamping screw nuts applied to said shanks and engaging with the outer sides of said standards, and spacing screws arranged on the ends of said plate and bearing against the inner sides of said standards. 30

3. A paper winding machine comprising a base, rear standards arranged on the rear part of said base and adapted to support a supply roll of paper, front standards adjustable transversely on said base, a rewinding shaft journaled on said front standards, and a cutter mechanism comprising a relatively fixed blade provided at one end with an opening and at its opposite end with a slot, a movable blade adapted to coöperate with the fixed blade, a screw pivotally connecting corresponding ends of the blades and passing through the opening in said fixed blade and into one of said front standards, 40 and a screw passing through the slot of said fixed blade and into the other front standard. 45

ADAM ROSS.
